UNITED STATES PATENT OFFICE.

LESLIE STEVENS, OF GLEN RIDGE, NEW JERSEY, ASSIGNOR TO STEVENS MANUFACTURING CORPORATION, OF NEW YORK, N. Y., A CORPORATION OF DELAWARE.

DESIGN FOR A LOUD-SPEAKER DIAPHRAGM.

Application filed February 15, 1927. Serial No. 20,768. Term of patent 7 years.

To all whom it may concern:

Be it known that I, LESLIE STEVENS, a citizen of the United States, residing at Glen Ridge, in the county of Essex and State of New Jersey, have invented a new, original, and ornamental Design for a Loud-Speaker Diaphragm, of which the following is a specification, reference being had to the accompanying drawing, forming a part thereof.

Fig. 1 is a perspective view;
Fig. 2 is a face view; and
Fig. 3 is a sectional view of a loud-speaker diaphragm embodying my new design.

I claim:

The ornamental design for a loud-speaker diaphragm, as shown.

LESLIE STEVENS.
